(57) **CLAIM**

The ornamental design for a hanger for a toilet bowl tablet, as shown and described.

DESCRIPTION

FIG. 1 is a front elevation view of a hanger for a toilet bowl tablet showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is an in-use isometric view thereof; and,

FIG. 8 is a cross-sectional view taken along line 8-8 of FIG. 4.

The broken lines in FIG. 7 of the drawings depict environmental subject matter only and form no part of the claimed design.
